UNITED STATES PATENT OFFICE.

JOSEPH B. WILSON, OF CHICAGO, ILLINOIS, ASSIGNOR TO THE WESTINGHOUSE ELECTRIC AND MANUFACTURING COMPANY, A CORPORATION OF PENNSYLVANIA.

TURBINE-CONTROLLING MECHANISM.

1,238,374.

Specification of Letters Patent. Patented Aug. 28, 1917.

Application filed June 22, 1912. Serial No. 705,273.

To all whom it may concern:

Be it known that I, JOSEPH B. WILSON, a citizen of the United States, and a resident of Chicago, in the county of Cook and State 5 of Illinois, have made a new and useful Invention in Turbine-Controlling Mechanism, of which the following is a specification.

This invention relates to turbine-controlling mechanism.

10 One of the objects is to maintain a constant speed at a given load irrespective of pressure of the steam supplied to the system.

As generally practised, turbines have heretofore been provided with governors 15 which control a valve or valves through a relay or relays so that the positions of the valves will determine the amount of steam fed into the turbine. This construction has generally been sufficient to take care of regulation when the fluid pressure supplied is 20 practically constant, but it has not proved to be satisfactory where the fluid supplied varies in pressure. In practice it has especially been proved unsatisfactory in connection with mixed pressure turbines; that is, a turbine operating on exhaust steam the supply of which is adapted to be augmented by steam at higher pressure should the exhaust steam become depleted or fail.

25 According to my invention, the turbine may be connected to the exhaust of a high pressure engine, and in addition to this, have connection with a source of high pressure steam, as for example, a boiler. In such an event a constant speed would be maintained at a given load whether there happened to be more than enough or just enough exhaust steam available to carry the load; for example, at half load if the pressure 30 in the line were ten pounds and more exhaust steam were available than was necessary to carry the load, the excess steam would be permitted to escape to atmosphere, or be carried off or shunted around the turbine. If the pressure in the main should drop, due to a decrease in the exhaust steam supply, the valve would open wider to accommodate the steam at the decreased pressure without necessitating a change in the 35 speed.

This invention is also applicable to a high pressure condensing turbine driving a constant load.

In the drawings:

55 Figure 1 is a diagrammatic view of a tur-

bine receiving motive fluid supply in accordance with my invention; and

Fig. 2 is a similar view of a slightly modified form.

Referring now to the drawings by numerals of reference, 1 designates a turbine here shown as a low pressure turbine and which is adapted to drive a constant load, as for example, a generator 2. The turbine 1 is here shown as being provided with a supply pipe 3 receiving the exhaust from a high pressure unit illustrated as a reciprocating engine 4. The pipe 3 is provided with a blow-off valve 5 and between the ends of pipe 3 is a valve casing 6 in which there is a balanced piston valve 7 adapted to be seated upon the seats 8 and 9 of the valve casing 6. A valve stem 10 is connected to the valve 7 and carries a collar 11 against which one end of a spring 12 bears, this spring being 60 about equal to the normal pressure of the steam entering the turbine. The other end of the spring rests upon a seat 13 on the valve casing 6. Connected by a bracket to the valve casing 6 is shown a high pressure 65 valve casing 14 receiving steam from high pressure, as for example, a boiler through the pipe 15 and discharging it through a pipe 16 into the pipe 3. Within the valve casing 14 is a balanced valve of the usual 70 construction having a stem 17 with a slotted extension 18 thereon in which is provided a sliding block 19 on a lever 20, one end of which is connected to a bracket 21 by a link connection 22, the other end of the lever 20 75 being connected to a piston rod 23 on the end of the piston 24 in the cylinder 25. The cylinder 25 is provided with ports 26 and 26' adapted to admit fluid into the cylinder 80 on opposite sides of the piston 24 and exhaust it therefrom in accordance with the position of the valves on the relay stem 27 which admit fluid to said cylinder. The relay stem 27 is provided with valves 28 and 29 which are adapted to cover and uncover 85 the ports 28' and 29' respectively with collars 30 and 31 acting as abutments or stops to prevent leakage of oil. The pipes 32 and 33 connected to the relay cylinder 34 are 90 exhaust pipes, while the pipe designated by 35 is a supply pipe to admit oil into the relay and through it into the cylinder 25. The relay stem 27 is illustrated as being connected to a floating lever 36, one end of which is connected to a gov- 95

100

105

110

ernor or speed responsive device, the other end of the floating lever 36 being connected to the stem 38 of the piston 39 in the cylinder 40. The stem 38 is provided with a seat 41 against which bears a spring 42 one end of which rests against a seat 43 in the bracket 44 so that the normal tendency of the spring 42 is to seat or exert a downward pressure upon the piston 39. Leading from 5 the pipe 3, preferably at some convenient point between the pipe 16 and the inlet to the turbine, is a pipe 45 which communicates with the inlet port 46 on the under side of the piston 39. At another convenient point, 10 as for example the exhaust end of the turbine 1, is a pipe 47 which leads into the cylinder 40 above the piston 39 and admits pressure to the port 48 of the cylinder 40.

Inasmuch as the pipe 45 communicates 20 with the conduit 3 in advance of the inlet to the turbine and also communicates with the cylinder 40 on one side of the piston 39, and the pipe 47 communicates with the exhaust end of the turbine 1 and with the cylinder 40 25 on the opposite side of the piston 39, the piston 39 will be affected by differences of pressure existing in the pipes 45 and 47; for example, if the normal pressure in the pipe 3 were 14½ pounds and the vacuum at the 30 exhaust end of the turbine happened to be 1 pound absolute, there would be a definite position for the piston 39. If the pressure in the pipe 3 should drop below 14½ pounds or increase above it, the piston 39 would be 35 affected. If the vacuum at the exhaust end of the turbine were reduced, there would be an increase of pressure in the pipe 47, and although the pressure in the pipe 3 remained 40 constant, the piston 39 would be affected because there would be a difference of pressures on opposite sides of the piston 39.

It will, therefore, be apparent that any 45 change in the pressure in the pipe 3 will be felt by the piston 39 irrespective of the pressure in the pipe 47, and any variation in pressure in the pipe 47 will be felt by the piston 39 irrespective of the pressure in the pipe 3.

Now, suppose the turbine 1 is operating at 50 its full load and that there is enough exhaust steam from the reciprocating engine to maintain the proper speed; in the event that the pressure in the pipe 3 falls the piston 39 will descend because the drop in pressure in pipe 45 will cause a drop in pressure 55 on one side of the piston 39 and the descending of the piston 39 will operate the oil relay stem 27 to open the port 29' and admit fluid through the port 26' to the under side of the piston 24 which in raising will cause the valve 7 to open more to accommodate the steam at the reduced pressure so as to maintain the speed of the turbine 1. If the continued upward movement of the valve 60 65 7 fails to supply sufficient exhaust steam to

maintain the desired speed on the turbine 1, a movement of lever 20 beyond the full open movement of the valve 7 will unseat the high pressure valve in the casing 14 and admit enough steam at boiler pressure to augment 70 the supply of low pressure steam sufficient to maintain the required speed. If, now, an additional amount of low pressure steam is available; that is, suppose there is an abundance of low pressure steam being supplied 75 from the reciprocating engine, or too much high pressure steam, the pressure will increase; the piston 39 will be raised; the oil relay will admit oil or similar fluid to the top of the piston 24 and exhaust it 80 from the bottom of the cylinder 25 so that the piston 24 will have a downward movement at first effecting the seating of the valve in the casing 14 and moving the valve 7 in a seating direction until just enough 85 steam at low pressure passes through the pipe 3 to maintain the desired speed of the turbine. It is to be understood that the block 19 has a lost motion or sliding movement in the slotted projection 18 so that the valve in the casing 14 does not begin to unseat until the valve 7 has moved to its full 90 extent. The function of the blow-off valve 5 will be obvious, it being generally understood that devices of this kind are 95 placed in lines for the purpose of relieving excess pressure in the pipe to which they are attached, so in this case any excess pressure in the pipe 3 will be relieved through the blow-off valve 5.

It is to be understood that the governor 100 or speed responsive device 37 operates in the usual way performing its usual functions, my invention consisting in making the pressure drop through the unit vary with the governor movement and having a compensating device with the governor to control the inlet pressure by making the valve position not only vary to suit the speed but also to suit the variations in the fluid pressure supplied; further, to so combine the mechanism that a certain speed will be maintained for a certain load irrespective of variations in the fluid supplied from the low pressure source for if the fluid supplied from 110 that source is insufficient, fluid from an additional source may be admitted.

In Fig. 2 I have shown a slightly modified form of a turbine-controlling system in which the turbine 1 is supplied from a pipe 3 receiving exhaust steam from a reciprocating engine 4. Between the ends of the pipe 3 is a valve casing 6' having a balanced valve 7' therein and adapted to be seated on seats 8' and 9'. Leading from the valve 7' 115 is a stem 10' on one end of which is a piston 50 in a cylinder 51. Above the cylinder 51 is shown a cylinder 52 having a piston 53 therein, the stem 54 of which is provided with a seat 55 against which one end of a 120

125 130

spring 56 bears, the other end of said spring bearing against a yoke 57. The piston stem 54 is connected to one end of a floating lever 58, the other end of which is connected to a link 59 on the governor 37'. Between the ends of the lever 58 is an oil relay stem 27' corresponding to the oil relay described in connection with Fig. 1, which admits fluid to the opposite sides of the piston 50 through the ports 60 and 61. The pipe 62 leads from the valve casing 6' to the cylinder 52 on the under side of the piston 53, while a pipe 63 leads from the cylinder 52 on the opposite sides of the piston 53 to the turbine 1. 5 is the blow-off valve in the pipe 3. The pipe 64 connected to the pipe 3 is provided with a valve casing 65 in which is a balanced valve 67 similar to that designated by the reference numeral 7' and is connected by a flexible connection 68 to the valve 7'. The pipe 64 may be connected to another engine similar to the one designated 4, or may be connected to boiler or auxiliaries if desired, the said pipe 64 simply leading from another source of supply.

The operation of the mechanism illustrated in Fig. 2 is similar to that described in Fig. 1, the governor 37' acting in its usual way, but should the supply in the pipe 3 fail, the piston 53 would move downward, operating the oil relay so as to push the piston 50 upward, opening the valve 7'. If, on the other hand, the supply became excessive, the piston 53 would be moved up; the oil relay would admit fluid to the upper side of the piston 50 and impart a closing movement to the valve 7'.

In the foregoing description it will be obvious that the regulation of the turbine will be such that a constant speed will be maintained for a constant load irrespective of the pressure within the pipe 3 and that the compensating device assisting the governor will position the valves in respect to the governor in accordance with the pressure maintained.

Having thus described my invention, what I claim is:

1. The combination with a turbine, a supply pipe, a valve in the supply pipe, and a speed responsive device controlling said valve, of a single piston responsive to variations in pressure in the supply pipe and at the exhaust end of the turbine for changing the position of the valve independent of the speed responsive device.

2. A turbine, a conduit leading steam into said turbine, a valve in said conduit, a governor for controlling said valve, a piston for controlling said valve, a cylinder surrounding said piston, a pipe leading from the cylinder to the conduit, a pipe leading from the cylinder to the turbine, and an oil relay responsive to the piston and for operating said valve.

3. A turbine control mechanism, comprising a source of fluid pressure for the turbine, a valve for controlling the delivery of fluid from said source to the turbine, a valve motor responsive in operation to variations in the pressure at the exhaust of the turbine for actuating said valve, and an auxiliary valve for at times delivering high pressure motive fluid to the first mentioned valve.

4. A turbine control mechanism, comprising a source of fluid pressure for the turbine, a valve for controlling the delivery of fluid from said source to the turbine, a valve motor responsive in operation to variations in the pressure at the exhaust of the turbine for actuating said valve, an auxiliary valve for at times admitting an additional supply of motive fluid to the first mentioned valve, and a speed responsive governor for controlling the operation of the valve motor.

5. In combination with a turbine, a control mechanism comprising a source of low pressure motive fluid, a governor, a valve controlled by said governor for delivering fluid to the turbine, a source of high pressure motive fluid, a valve for controlling the delivery of fluid from said high pressure source to said first mentioned valve, and means responsive to variations in the pressure of fluid delivered to said first mentioned valve for controlling the operation of the first mentioned valve independently of the governor.

6. In combination with a turbine, a control mechanism comprising a source of low pressure motive fluid, a source of high pressure motive fluid, a high pressure valve for delivering fluid from said high pressure source to augment the low pressure fluid supply, a low pressure valve for controlling the delivery of fluid from said low pressure source and of the fluid from the high pressure valve to said turbine, a governor responsive to speed variations of the turbine for controlling the operation of each of said valves, and means responsive to variations in pressure of the fluid delivered to the low pressure valve for controlling the operation of the low pressure valve independently of the governor.

7. In combination with a turbine, a control mechanism comprising a source of low pressure motive fluid, a source of high pressure motive fluid, a high pressure valve for delivering fluid from said high pressure source to augment the low pressure fluid supply, a low pressure valve for controlling the delivery of fluid from said low pressure source and of the fluid from the high pressure valve to said turbine, a governor responsive to speed variations of the turbine for controlling the operation of each of said valves, and means responsive to pressure variations of the fluid delivered to the low

pressure valve for controlling the operation of both of said valves independently of the governor.

8. In combination with a turbine having a fluid inlet port, a control mechanism comprising a passage communicating with said port and for delivering fluid to the turbine from a source of low pressure supply, a passage communicating with an auxiliary source of supply and with said port for delivering an auxiliary supply of motive fluid to the turbine, a separate valve for controlling the delivery of motive fluid through each of said passages, a governor responsive to variations in speed of the turbine for controlling the operation of said valves, and means responsive to variations in the pressure of fluid from said source of low pressure supply for controlling the operation of both of said valves independently of the speed of the turbine.

9. In combination with a turbine, a high pressure source of fluid supply, a low pres-

sure source of fluid supply, valves for controlling the delivering of fluid to the turbine from both of said sources, a speed responsive device driven by the turbine, a motor responsive to the operation of said speed responsive device for controlling the operation of said valves to vary the amount of fluid delivered to the turbine in response to variations in the speed thereof, and means responsive to the differential pressure between the low pressure source of supply and the turbine exhaust for moving both valves toward a closing position independently of the operation of the speed responsive device, in response to an increase in the differential pressure.

In testimony whereof, I have hereunto 40
subscribed my name this 20 day of June,
1912.

JOSEPH B. WILSON.
